(57) **CLAIM**

The ornamental design for the shoe sole, as shown and described.

DESCRIPTION

FIG. 1 is a front elevational view of a shoe sole showing the new design.

FIG. 2 is a rear elevational view thereof.

FIG. 3 is a right side elevational view thereof.

FIG. 4 is a left side elevational view thereof.

FIG. 5 is a top plan view thereof.

FIG. 6 is a bottom plan view thereof; and,

FIG. 7 is a perspective view thereof.

The dashed lines seen in the drawings depict a representation of a stitching line.
